(57) **CLAIM**

The ornamental design for a display screen or portion thereof with graphical user interface, as shown and described.

DESCRIPTION

FIG. 1 is a front view of a display screen or portion thereof with graphical user interface showing a first embodiment of my new design;

FIG. 2 is a front view thereof, shown in an alternate position and with an alternate environment;

FIG. 3 is a front view thereof, shown in an alternate position and with an alternate environment;

FIG. 4 is a front view thereof, shown in an alternate position and with an alternate environment;

FIG. 5 is a front view thereof, shown in an alternate position and with an alternate environment;

FIG. 6 is a front view thereof, shown in an alternate position and with an alternate environment;

FIG. 7 is a front view of a second embodiment of the display screen or portion thereof with graphical user interface; and, FIG. 8 is a front view of a third embodiment of the display screen or portion thereof with graphical user interface.

The broken lines showing the display screen or portion thereof form no part of the claimed design. The dot-dash circle is claimed subject matter. The broken lines of the remainder of the graphical user interface form no part of the claimed design.

The dot-dash circle is claimed subject matter.

1 Claim, 8 Drawing Sheets
